(57) **CLAIM**

The ornamental design for an adjustable bed foundation, as shown and described.

DESCRIPTION

FIG. 1 is a perspective view of an adjustable bed foundation in accordance with the present invention; and,

FIG. 2 is a side view of an adjustable bed foundation of FIG. 1.

The broken lines shown in the Figures that are immediately adjacent to the shaded area represents boundaries of the claim. All other broken lines illustrates portions of the adjustable bed foundation and form no part of the claimed design.
